UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed June 13, 1928. Serial No. 284,976.

This invention relates to web-manifolding, carbon-stripping typewriting machines, in each of which there is often employed an additional web or sheet for a condensed record, 5 upon which are closely manifoldeled the entries from a long succession of fan-fold forms.

A fan-fold work-web may be considerably narrower than the condenser record-web used with it, and the side margins of the latter 10 may be left exposed, to be held during manipulation of the overlying work-web.

A manually-operable device is provided in my co-pending application, Serial No. 273-452, filed April 28, 1928, for clamping a record-web at both the introductory and delivery side of the platen, to hold the record-web taut against the platen when the latter is being displaced upwardly, thereby preventing the record-web from falling away from the 20 platen onto the underlying straightened work-web and becoming kinked or fouled. The record-web clamp, disclosed in said co-pending application, was operated by a lever, which was disposed near the usual lever 25 which locks the platen down in typing position.

It is a feature of the present invention to provide automatic means for clamping a record web or sheet at both sides of the platen, 30 the same to be operated upon a releasing movement of the platen locking lever.

The record-web clamp is also locked in effective position by a lock which is mounted on the platen-displacing frame, to be effective 35 in its raised forward carbon-stripping position.

Said record-web clamp is also released automatically upon lowering the platen-frame to typing position.

40 In practising the present invention as applied to an Underwood continuous billing typewriting machine, a clamping device, including a paper-table and a pair of clamps, is mounted on the platen-displacing frame, partly at the introductory side of the platen, and partly at its delivery side. All of the 45 clamps are normally ineffective, and are operatively connected to a platen-displacing-frame-locking-lever, so as to be made effective by an unlocking movement of said lever,

which is also effective to raise the platen slightly off the lower feed-rolls. A device is mounted on the platen-displacing frame which locks the clamps in effective position upon swinging the frame upwardly to carbon-stripping position. The locking device is automatically released upon lowering the platen to typing position, and the clamps are concomitantly swung upward to ineffective positions.

It is a feature of the present invention to arrange the operative connection between the record-web clamps and the platen-frame locking-lever, whereby the record-web is not released by the lower feed-roll until it is gripped by the record-web clamps. Another feature resides in the provision of means, whereupon, when lowering the platen from its raised carbon-stripping position, the record-web clamps are maintained in locked engagement with their respective tables until the platen is locked in engagement with the lower feed-rolls. From the two above-noted features, the advantage results that the record-web is always clamped against accidental displacement on the platen.

A further feature resides in the provision of a simple device for locking the record-web clamps in engagement with their respective tables, which device is initially moved adjacent its effective locking position by operation of the platen-displacing-frame-locking-lever, and is subsequently locked by forward movement of the platen-displacing frame. This advantageous arrangement of the locking device permits a platen-raising operation of the locking-lever without causing the record-web clamps to become locked, and necessitating subsequent unlocking.

Other features and advantages will hereinafter appear.

In the accompanying drawings, Figure 1 is a fragmentary cross-sectional view, front to rear, through an Underwood continuous-billing typewriting machine, having my invention applied thereto.

Figure 2 is a diagrammatic view illustrating the coaction of certain parts with a platen-displacing-frame-locking-lever which is shown partly operated.

Figure 3 is a view similar to Figure 1, in which the locking-lever is shown moved to its rearmost position.

Figure 4 is a disassembled perspective detail view of a locking pin and finger of the present invention.

Figure 5 is a fragmentary detail view illustrating how the feed-roll-release mechanism may be mounted to clear the platen-displacing frame.

Figure 6 is a fragmentary front perspective view of the structure shown in Figure 1.

Figure 7 is a diagrammatic view illustrating how the record-web clamps remain locked in effective positions when the platen is in its raised carbon-stripping position.

Figure 8 is a diagrammatic view illustrating how the clamp-locking device of the invention is automatically released upon lowering the platen from its raised carbon-stripping position.

The present invention is illustrated in connection with an Underwood continuous-billing typewriting machine in which types 10 strike against a platen 11 on a platen-shaft 12 journaled in a right-hand side plate 13 and a left-hand side plate 14 of a platen-displacing frame 15 which is pivotally mounted on a carriage 16. Instrumentalities for line-spacing the platen include a ratchet-wheel 17 operatively connected to a gear-wheel 18 which, acting through a pinion 19 on a stub-axle 20 fast on the carriage, rotates a gear-wheel 21 on the platen-shaft 12. Lower feed rolls 22 engage against the platen 11. Instrumentalities for guiding a multiple-ply work-web 23 between the feed-rolls of the platen may include a rear paper-table 24.

Carbons 25 may be held interleaved between the plies of the web 23 by a carbon-carrier 26 which runs on a track 27, the forward end of which is supported in the rear of the carriage by a pair of brackets 28 fastened to the carriage. Two side edge guides 29 for the work-web 23 may be mounted on a cross-rod 30 extending between the brackets 28 and guide the web laterally as it is conducted to the platen.

The parts described hereinbefore may be of usual construction employed in an Underwood standard continuous-billing typewriting machine.

A typewriting machine embodying the present invention may be advantageously used for manifolding a line of data on each of a series of sets of short forms 31 previously printed on the work-web 23 and making a condensed record of such data on a wider underlying record web or sheet 32. The record-web is laterally positioned on the platen by means hereinafter described, so that both of its side edge portions extend out beyond the side edges of the web 23. For making a neat condensed record, it is desirable to hold the record-web taut around the platen while the

latter is in its raised position, lest it fall onto the underlying work-web and be kinked or fouled thereby.

To this end, means are provided for holding the record-web taut on the platen while a typed set of forms is manipulated for carbon-stripping purposes. One embodiment of the record-web-holding means includes an auxiliary rear paper-table 35 over which the record-web may be conducted. The table 35 is disposed above the usual rear paper-table 24 over which the work-web is conducted. The table 35 includes a plate body 36, each end of which may be fastened as by riveting to an inreaching flange 37 which is integrally joined to a downward extension 38 of an inreaching bracket 39 which may be integrally joined to the adjacent side plate of the platen-displacing frame 15.

To the inner face of each extension 38 may be riveted an upwardly and forwardly inclined standard 40 whose upper end is curled for engaging with a snug fit around a gage-bar-supporting rod 41. As illustrated in Figure 6, the inner face of the right-hand extension 38 may serve as a side edge guide for the record-sheet 32. To provide gaging devices at the delivery side of the platen for the work-web 23, an angle-bar 43 extends between the rods 41 and may be fastened to their upper ends as by riveting, so that a flange-member 44 of the angle-plate is inclined downwardly toward the platen substantially tangent thereto. The upper edge of the member 44 may serve as a tearing-off gage for the forms 31, a succession of which are divided by perforated lines indicated at 45. To provide for adjusting the upper edge of the flange 44 toward and away from the printing line, each rod 41 may be adjustably clamped to the standard 40 by thumb-screws 46.

Two angle plates 47, each having a relatively long base-member 48 with a lengthwise slot 49 therein and a short upwardly-reaching arm 50, are mounted for lateral adjustment upon the flange-member 44 by means of screws 51 which pass through the slots and are threaded in tapped holes 52 in the member 44. The arms 50 are spaced apart slightly more than the width of the work-web 23, the typed portion of which may pass between the arms to be laterally guided thereby.

To co-operate with the auxiliary table 35 for holding the record-web, each of two flexible clamping arms 60 is mounted on a collar 61, which is adjustably fastened by set screws 62 on a rock-shaft 63 extending between the side plates 13 and 14. The shaft 63 is journaled at its right end on an inreaching pivot-screw 64 in the side plate 13. Mounting the shaft 63 in the manner described allows other parts to be assembled on it and the whole to be conveniently assembled as a unit on the platen-displacing frame. From its collar 61, each flexible arm 60 ex-

tends downwardly and forwardly adjacent the table 35 and its lower end portion is enclosed in a paper-gripping rubber shoe 65 which bears squarely against the table 35 adjacent its lower edge.

Means for clamping the exposed side edge portions of the record-web 32 at the delivery side of the platen includes a paper-table 66 mounted on a cross-bar 67 between the sides of the platen-displacing frame 15. The lower portion of the table 66 is disposed substantially tangent to the platen, and an upper rear portion 68 is bent upwardly to deflect the record-sheet above the rock-shaft 63.

To co-operate with the table 66, two clamping arms 70 are mounted loosely on the rock-shaft 63, one arm being positioned outwardly a short distance from the adjacent arm 60. Each arm 70 may have a short upreaching portion 71 with an aperture through its lower end to receive said shaft and a member 72 integrally joined to the top of the upreaching portion 71 and extending therefrom forwardly near the lower edge of the table 66. The forward end portion of each member 72 turns downward toward the table 66 and then terminates in an inreaching tab 73 having a paper-gripping rubber shoe 74.

An operative connection between the clamping arm 70 and the rock-shaft 63 includes a spring 75 coiled around the shaft between two adjacent clamping arms 60 and 70. One end of each spring is fastened to the screw 62 in the adjacent collar 61 and the other end of the spring extends upwardly along the upreaching arm portion 71 and terminates in a hook-member 76 which engages behind the upreaching portion. Each spring 75 is arranged with initial tension which normally urges the associated arm 70 toward the table 66.

To enable clockwise rotation of the rock-shaft 63 to raise the rubber-covered tabs 73 from the table 66, an upreaching arm 77 is rigidly fastened on the shaft 63 outwardly from each clamping arm 70 and closely adjacent thereto by means of a hub 78 which may be secured to the rock-shaft 63 in any suitable way. The upper end of each arm 77 has an inreaching extension 79 which engages against the forward edge of the upreaching tongue 71 on the clamping arm 70.

The shaft 63 is normally urged clockwise against a stop hereinafter described by instrumentalities including a downwardly-extending arm 81 fastened securely on the shaft adjacent its left end and a contractile spring 82 which has one end fastened to a pin 83 in the arm 81 and the other end fastened to a pin 84 in the left-hand side plate 13. The action of the spring 82, tending to rotate the arm 70 clockwise, is stronger than the action of the springs 75 and in consequence thereof the arms are normally disposed in ineffective positions above the paper-table

66. The arms 60 are mounted on the collars 61 so as to be disposed above the paper-table 35 when the shaft 63 is held in its extreme clockwise position by the spring 82.

In a web-manifolding typewriting machine of the type disclosed in the patent to Wernery & Smith, No. 1,132,055, dated March 16, 1915, it is usual to provide instrumentalities for locking the upwardly displaceable platen-frame down in typing position. It is necessary to release these instrumentalities preparatory to raising the platen for stripping the carbons.

It is a feature of the present invention to provide platen-frame-locking instrumentalities which co-operate with mechanism, to be described hereinafter, which manipulates the record-web-clamping arms. To this end, a laterally-disposed inreaching locking pin device generally designated as 85 is fastened in the platen-frame side plate 14, and a similar locking pin device 86 is fastened in the side plate 13. The pin devices 85 and 86 are positioned a short distance above and a short distance forward from a usual cross-rod 87 which extends between the sides of the carriage 16 and forms a stop for a usual depending stop-portion 88 of the side plates 13 and 14.

The pin-device 85 (see Figure 4) includes a boss-portion 90 disposed against the side plate 14, a reduced stud-member 91 having a threaded extension 92 and a collar 93 which fits loosely over the stud-portion and is shorter than the latter. For a purpose to presently appear, a locking trigger generally designated as 95 is mounted on the exposed outer end of the stud 91 and a nut 96 screws on the threaded extension 92 to hold the collar and trigger in place. The pin-device 86 on the side plate 13 may be of usual construction.

To co-operate with the locking pin 85, a locking lever generally designated as 100 has its lower end pivotally mounted on the cross-rod 87 adjacent the left side of the carriage 16. The lower end of the lever is enlarged and may have an irregular form as illustrated in Figure 7, which includes a stop-lug 101, a locking slot 102, and a cam-shoulder 103.

The slot 102 has a width at all points for engaging about the collar 93 with a running fit. The slot also serves as a cam, and, for a purpose to presently appear, the rear end portion of the slot has a circumferential dwell 104 centered about the axis of the rod 87. A forward portion of the slot is formed with a lower cam edge 105, effective to raise the pin 85, upon movement of the lever 100 rearwardly. An integral tongue-member 106 on the lower end of the lever 100 extends forwardly below the mouth of the slot 102 and has its upper edge shaped for forming a continuation of the cam edge 105. The extreme forward end of the tongue 106 has an

125

130

upwardly-turned hook-portion 107 which is effective to engage against the pin 85 and arrest the lever 100 when the latter is moved to its rearmost position.

5 The lever 100 is normally urged forwardly by a spring 108 which is coiled about the rod 87 and has its rear end hooked over the top edge of the paper-table 24 and the other end hooked in a usual collar on the rod 87, which is rotatably mounted in the carriage 16. The lever 100 is arrested in its foremost position by the stop-lug 101 engaging against the forward face of the table 24.

10 In the foremost position of the lever 100, the collar 93 of the pin device 85 is disposed in the dwell 104 adjacent the rear end thereof (Figure 1). An inreaching pin 110 carrying a friction reducing sleeve 111 is fastened on the lever above the rod 87. A cam edge 112 is provided on the forward side of a downwardly and forwardly inclined extension 113 of the arm 81, and is normally urged by the spring 82 against the sleeve-bearing pin 110 which thus serves to limit the upward 15 swing of the clamping arms 60 and 70 away from their respective tables.

15 According to one use of a continuous billing typewriting machine, embodying the present invention, after typing a usual line of data on a form, the clamping arms 60 and 70 being normally released, both the work-web 23 and the record-web 32 are line-spaced ahead by the usual line-spacing instrumentalities enough to give the desired continued 20 record spacing on the web 32.

25 The lever 100 is then pushed rearwardly by a finger of the left hand of the operative which engages a finger piece 114 on the end of the lever. The pin 110, acting on the cam edge 112 of the arm 81, is quickly effective to cause the clamping arms 60 and 70 to be moved against their respective tables for gripping the record-web 32, and the dwell 104 moves rearwardly from the pin 85. As 30 illustrated in Figure 2, the pin 110 will move to the rear enough to cause the arms 60 and 70 to grip the record-web 32 against their respective tables before the cam edge 105 of the slot 102, acting on the pin 85, will cause 35 the platen 11 to be raised off the feed-rolls 22. This advantageous arrangement provides for the record-sheet to be clamped against misplacement in the machine during the raising of the platen 11.

40 Upon movement of the lever 100 to its rearmost position (Figure 3), the platen will have been raised clear of the feed-rolls. Should it be desired to type two or more forms before severing them from the work-web 23, the latter can be pulled ahead to bring the leading edge of the typed form to the tearing-off gage 44, which is positioned to have the first writing line of the 45 next succeeding form brought to the printing line.

50 After the finger-piece 114 is released, the springs 82 and 108 will co-operate in restoring the platen 11 to typing position. Movement of the lever 100 over the latter part of its travel is not prevented by the clamps 60 and 70 having already engaged their respective tables, since the spring 75 will yield and allow the shaft 63 to be further rotated by final movement of the lever 100. Also because of their flexibility, the arms 60 will yield and will not prevent full rearward movement of the lever.

55 After typing and gaging a form, the platen may be elevated, the carbons stripped and the typed forms may be torn off along a perforated line 45. In carrying out these operations, the lever 100 will be pushed to its rearmost position and the pin 110 in the lever will move outwardly along the cam edge 112 to its lower extremity (Figure 3). This movement of the pin 110 swings the arm 81 counterclockwise about the pivot-shaft 63 sufficiently to bring a square locking pin 115, securely fastened on the right side of the arm 81, to a position adjacent the end of a finger 116 of the trigger 95. The end of the finger has an offset or a square notch 117 arranged for having the pin 115 seated therein when the platen-displacing frame 15, which carries the arm 81, is swung upward and the lower end of the arm rides over and past the sleeved pin 110, which will permit the spring 82 to pull the arm 81 counterclockwise. To keep the notched end of the finger 116 in position for engaging the pin 115 while both the pin and the finger are moving clockwise, the lower end of a depending finger 118 of the trigger 95 is arranged to ride over the rod 87 and maintain the notched finger 116 in position to engage the pin 115 as soon as it is swung counterclockwise by the spring 82 about the shaft 63. Thereafter, the pull of the spring 82 holds the pin locked in engagement with the notched finger while the platen-frame is being displaced upwardly to Figure 7 position for straightening the web 23. While the platen-frame is being swung forward and upward, the operative's finger will be removed from the finger-piece 114 on the upper end of the lever 100, and the latter will be swung forward to Figure 7 position by the spring 108.

60 It will be noted that in the Figure 7 position the record-web, being clamped at both sides of the platen, is held securely against falling away from the platen on the underlying work-web and being kinked or otherwise fouled as the work-web is manipulated. The carbons may be stripped in the usual way and the platen lowered.

65 It is a feature of the present invention that the arms which clamp the record-sheet on the tables 35 and 66 are automatically released by the lowering of the platen to typing position. To this end, the shoulder 103 on the lever 100 is provided with a forward cam edge 120

which is disposed for engagement by the pin 85 when the latter is lowered from the raised carbon-stripping position of the platen. The pin, as it is swung down, cams the shoulder 103 and the lever 100 clockwise as indicated in Figure 8. While the pin 85 descends past the lower end of the cam edge 120 in front of the open end of the slot 102, the descending trigger finger 118 strikes the cross-rod 87 and swings the notched finger 116 up out of engagement with the square locking pin 115 and releases the arm 81 which controls the clamping arms 60 and 70. The lever 100 is likewise released when the pin 85 clears the cam shoulder 103.

It will be noted that when the cam slot 102 in the lever 100 has been swung counterclockwise to the Figure 2 position by the spring 108, the slot's co-action with the pin 85 has moved the platen down into engagement with the feed-rolls 22. Further movement of the lever 100 counterclockwise has no further effect on the platen since the pin 85 is now in the dwell 104, but the further counterclockwise movement permits the arm 81, which is caused to follow the lever closely by the spring 82, to effect the raising of the clamping arms 60 and 70 from their respective tables. A new cycle of operations may now begin by typing the next form.

A locking member 121, which co-operates with the locking lever 100, is mounted on the rod 87 adjacent the side plate 13 and has a cam shoulder 122 for engagement by the pin 86. The shoulder has a lower cam edge 123 which is similar to the upper edge of the slot 102, and engages over the pin 86.

It will be seen that the record-web 32, after being inserted in position to be clamped by the clamping arms 70, will always be gripped, either against the platen 11 by the feed-rolls 22 or against the tables 35 and 66 by the clamping arms 60 and 70 respectively. To provide for truing the record-web in case it is accidentally displaced while being inserted or afterwards, the feed-rolls 22 may be connected to a usual feed-roll-release lever 125 by usual instrumentalities including a cam shaft 126, a crank arm 127 and a link 128 which may be disposed between a usual gear 129 and a right hand side plate 130 of the carriage 16 (Figure 5).

It can be readily seen by those skilled in the art that a continuous billing typewriting machine embodying the present invention can be advantageously used for doing several different kinds of work besides that described hereinbefore.

Variations may be resorted to within the scope of the invention, and portions of the improvements may be used without others.

Having thus described my invention, I claim:

1. In a web-manifolding, carbon-stripping typewriting machine, the combination of a

platen-displacing frame, a platen in said frame around which may be fed from the rear a multiple-ply, carbon-interleaved work-web and a wider underlying record-web having both side edges exposed, lower feed-rolls, a lever for locking said platen down against said feed-rolls, a device on said frame for clamping said record-web at the introductory side of said platen, a device on said frame for clamping said record-web at the delivery side of said platen, said clamping devices being disposed in ineffective positions against spring pressure while typing is performed, a connection between said locking lever and said clamping devices for making the latter effective upon an initial unlocking movement of said lever, said record-web remaining engaged between said platen and said feed-rolls during said initial movement of said lever, means for raising the platen slightly off said feed-rolls upon a complete unlocking movement of said lever, whereby said work-web may be advanced relative to said record-web, instrumentalities arranged for locking said clamping devices in their effective positions, upon raising said platen-frame to carbon-stripping position subsequent to the complete unlocking movement of said lever, said clamping devices remaining effective upon displacement of said frame and holding said record-web against falling away from said displaced platen onto said work-web and being kinked or fouled, and means effective for releasing said locking instrumentalities upon lowering said displaced platen, said last-named means becoming effective only after said platen has engaged said lower feed-rolls, the operation of said record-web clamps being thereby controlled relative to the engagement of said platen and said feed-rolls, so that the record-web is always gripped by said clamps or said feed-rolls.

2. In a web-manifolding, carbon-stripping typewriting machine, the combination of a platen-displacing frame, a platen in said frame around which may be fed from the rear a multiple-ply, carbon-interleaved work-web and a wider underlying record-web having both side edges exposed, lower feed-rolls, a locking lever for locking said platen down in typing position, said lever being also effective to raise said platen slightly off said feed-rolls when moved to its completely released position, a normally ineffective clamping device on said frame for clamping said record-web at the introductory side of said platen-frame, a normally ineffective clamping device on said frame at the delivery side of said platen for clamping the side edges of said record-web clear of said work-web, a connection between said lever and said clamping devices for making the latter effective upon an initial platen-unlocking movement of said lever, whereby said devices are made effective before said platen is raised off

said feed-rolls, releasable instrumentalities effective for locking said clamping devices in effective positions against spring pressure, said clamping devices remaining effective upon displacement of said frame to hold said record-web taut around said platen, whereby said record-web will be held against falling away from the raised platen onto said work-web and being kinked or fouled thereby.

3. In a web-manifolding, carbon-stripping typewriting machine, the combination of a platen-displacing frame, a platen in said frame around which may be fed from the rear a multiple-ply, carbon-interleaved, form-bearing work-web and a wider underlying record-sheet having both side edges exposed, lower feed-rolls, a lever for locking said platen down against said feed-rolls, said lever being effective upon full unlocking movement to raise said platen slightly off said feed-rolls, and means operatively connected to said lever and made effective upon initial platen-unlocking movement of the latter for clamping said record-sheet at both sides of the platen, said clamping means becoming effective before said platen is clear of said feed-rolls.

4. In a typewriting machine, the combination with a carriage, a platen-displacing frame on said carriage, and a platen around which may be fed from the rear a multiple-ply, form-bearing, carbon-interleaved work-web and a wider underlying record-sheet having both side edges exposed, of a lever normally effective for locking said platen down in typing position and movable to a platen-releasing position, wherein it is effective to raise said platen slightly, and clamping means under control of said lever arranged for clamping said record-sheet at both sides of said platen, movement of said lever to its platen-releasing position causing said clamping means to grip said record-sheet.

5. The structure described in claim 4, characterized by said clamping means being mounted on said platen-displacing frame, and said lever being mounted on the carriage.

6. The structure described in claim 4, characterized by said clamping means including a separate paper-table at the introductory side and at the delivery side of said platen, and a separate set of clamps for each table, said clamps being operatively connected to said platen-releasing lever.

7. In a typewriting machine, the combination with a carriage, a platen-displacing frame on said carriage, and a platen around which may be fed from the rear a multiple-ply, form-bearing carbon-interleaved work-web and a wider underlying record-sheet having both side edges exposed, of a lever normally effective for locking said platen down in typing position and movable to a platen-releasing position, wherein it is effec-

tive to raise said platen slightly, clamping means under control of said lever arranged for clamping said record-sheet at both sides of said platen, movement of said lever to its platen-releasing position causing said clamping means to grip said record-sheet, said clamping means including a separate paper-table at the introductory side and at the delivery side of said platen, a separate set of clamps for each table, said clamps being operatively connected to said platen-releasing lever, a lateral rock-shaft having both sets of said clamps mounted thereon, and an operative connection between said platen-locking lever and said rock-shaft.

8. In a typewriting machine, the combination with a carriage, an upwardly displaceable platen-frame, and a platen around which may be fed from the rear a multiple-ply, carbon-interleaved work-web and a wider underlying record-sheet having both side edges exposed, of a locking lever on said frame normally disposed in a forward position for locking said platen down, means effective upon a platen-releasing, rearward movement of said lever for raising said platen slightly, an auxiliary paper-table at the rear of said platen over which said record-sheet is conducted to the platen, a paper-table at the delivery side of said platen over which said work-web and said record-sheet are conducted rearwardly, a pair of clamping arms arranged for gripping said record-sheet against said first-named paper-table, a pair of clamping arms arranged for gripping the exposed side edge portions of said record-sheet against said paper-table at the delivery side of said platen, a lateral rock-shaft on which said clamping arms are mounted, and a connection between said shaft and said platen-locking lever including a depending cam-arm fast on said shaft and a laterally-extending pin on said lever arranged for engaging said cam-arm and swinging it counterclockwise, for rotating said shaft and swinging said clamping arms against their respective tables.

9. The structure described in claim 8, characterized by the platen-raising means including a lateral pin in said platen-displacing frame, and a cam edge on said lever engaging said pin, the rear portion of said cam edge having a dwell whereby initial movement of the lever rearwardly will not move said frame upwardly, the remainder of said cam edge being effective for camming said pin upwardly upon movement of said lever to its rearmost position.

10. The structure described in claim 8, characterized by means effective for locking the cam-arm in operated position, whereby the clamping arms operatively connected to said cam-arm are locked against their respective paper-tables.

11. In a typewriting machine, the combina-

- tion with a carriage, an upwardly-displaceable platen-frame, and a platen around which may be fed from the rear a multiple-ply, carbon-interleaved work-web and a wider underlying record-sheet, having both side edges exposed, of a locking lever on said frame normally disposed in a forward position for locking said platen down, means effective upon a platen-releasing rearward movement 5 of said lever for raising said platen slightly, an auxiliary paper-table at the rear of said platen over which said record-sheet is conducted to the platen, a paper-table at the delivery side of said platen over which said 10 work-web and said record-sheet are conducted rearwardly, a pair of clamping arms arranged for gripping said record-sheet against said first-named paper-table, a pair of clamping arms arranged for gripping the exposed 15 side edge portions of said record-sheet against said paper-table at the delivery side of said platen, a lateral rock-shaft on which said clamping arms are mounted, a connection between said shaft and said platen-locking lever including a depending cam-arm fast on said shaft and a laterally-extending pin on said lever arranged for 20 engaging said cam-arm and swinging it counterclockwise for rotating said shaft and swinging said clamping arms against their respective tables, the platen-raising means including a lateral pin in said platen-displacing frame, a cam-edge on said lever engaging said pin, the rear portion of said cam-edge having a dwell whereby initial movement of 25 the lever rearwardly will not move said frame upwardly, the remainder of said cam-edge being effective for camming said pin upwardly upon movement of said lever to its rearmost position, means effective for locking the cam-arm in operated position, whereby the clamping arms operatively connected to said cam-arm are locked against their respective paper-tables, and a yielding connection between the cam-arm and the clamping arms, whereby 30 said cam-arm may be swung sufficiently upon initial movement of the locking lever to cause said clamping arms to be effective and thereafter be swung an additional amount to locking position. 35
13. In a web-manifolding, carbon-stripping typewriting machine, the combination of a carriage, a platen-displacing frame on said carriage, a platen in said frame around which may be fed from the rear a multiple-ply, carbon-interleaved work-web and a wider underlying record-sheet having both side edges exposed, lower feed-rolls, a locking lever effective when disposed in its forward position for locking said platen down against said feed-rolls, instrumentalities effective upon full rearward releasing movement of said locking lever for raising said platen slightly off said feed-rolls, whereby said work-web 40 may be pulled ahead, means for clamping said record-sheet at the introductory and delivery sides of the platen, including a paper-table at each side of the platen over which said record-sheet is conducted, two sets of normally ineffective clamping arms, one set arranged for engaging against each paper-table, instrumentalities made effective upon initial rearward movement of said locking lever for moving said clamps against spring action into engagement with their respective paper-tables, instrumentalities effective for locking said clamps against their respective tables upon movement of said locking lever to its rearmost position, said locking instrumentalities remaining effective to grip said 45 record-sheet, while said platen-frame is displaced upwardly for straightening said work-web below said platen preparatory to stripping said carbons, and means effective for automatically releasing said locking instru- 50

mentalities upon lowering said platen-frame to typing position, whereupon said clamping arms are swung away from their respective tables to ineffective positions by said spring action.

5 14. The structure described in claim 13, characterized by said releasing means including a depending member carried by said platen-frame and disposed for striking a forced member of said carriage for operating said releasing means.

10 15. The structure described in claim 13, characterized by said releasing means including a depending member carried by said platen-frame and disposed for striking a forced member of said carriage for operating said releasing means, and by an arrangement of said releasing means, whereby said platen, upon being lowered from its upwardly-displaced web-straightening position, engages said lower feed-rolls to grip said record-sheet thereagainst before said clamping arms have released their grip on said record-sheet.

15 16. In a typewriting machine of the class described, the combination with a displaceable platen, around which may be fed from the rear a multiple-ply work-web interleaved with carbons and a wider underlying record-web having both side edges exposed, and lower feed-rolls, of means effective for gripping the record-web taut on said platen at both sides thereof when said platen is displaced in its carbon-stripping position, and instrumentalities effective for automatically releasing said record-web gripping means upon lowering said platen, said instrumentalities becoming effective only after said platen is in engagement with said feed-rolls, whereby said record-web is controlled against being displaced on said platen while the latter is being lowered to typing position.

20 17. In a web-manifolding, carbon-stripping typewriting machine of the class described, the combination with an upwardly displaceable platen around which a multiple-ply work-web interleaved with carbons, and an underlying record-web having both side edges exposed, may be fed from the rear, and lower feed-rolls, of means effective for gripping the record-web taut on said platen at both sides thereof, said means being normally ineffective and becoming effective concomitantly with the displacing of said platen upwardly to carbon-stripping position, instrumentalities arranged for making said gripping means effective before said platen is disengaged from said feed-rolls, instrumentalities effective for automatically releasing said record-web gripping means upon lowering said platen, said last-named instrumentalities becoming effective only after the platen engages said lower feed rolls, whereby said record-web is controlled at all times against slipping out of place on said platen.

25 18. The structure described in claim 17, characterized by means for locking said record-web clamping means in effective position, upon raising said platen toward a carbon-stripping position, and devices for automatically releasing said locking means, upon lowering said platen-frame toward typing position.

30 19. In a web-manifolding, carbon-stripping typewriting machine, the combination of a platen-displacing frame, a platen in said frame around which may be fed from the rear a work-web interleaved with carbons and a wider underlying record-web having both side edges exposed, lower feed-rolls, a spring-pressed lever for locking said platen down in typing position, a device at each side of said platen for clamping said record-web clear of said work-web, said device being normally ineffective, mechanism for making said clamping device effective upon an initial movement of said locking lever, instrumentalities for locking said clamping device in effective position, said instrumentalities being set by a final releasing movement of said locking lever in positions adjacent their effective locking positions, and means for making the upward displacement of said platen-frame in carbon-stripping position effective to move said instrumentalities to their effective locking positions, wherein said instrumentalities will hold said clamping device locked in effective position irrespective of the displaced position of said platen.

35 20. The structure described in claim 19, characterized by a device controlled by the locking lever for raising the platen slightly off the feed-rolls upon final releasing movement of said lever, and means for controlling the clamp-locking instrumentalities so that they are made ineffective by return to normal position of the spring-pressed locking lever prior to the displacement of the platen-frame to web-straightening position.
